UNITED STATES PATENT OFFICE.

PATRICK F. GUTHRIE, OF NUTLEY, NEW JERSEY, ASSIGNOR OF ONE-HALF TO EDMUND J. GUTHRIE, OF NUTLEY, NEW JERSEY.

CUSHION FOR VEHICLES.

No. 909,400.

Specification of Letters Patent.

Patented Jan. 12, 1909.

Application filed August 6, 1907. Serial No. 387,319.

To all whom it may concern:

Be it known that I, PATRICK F. GUTHRIE, a citizen of the United States, residing at Nutley, in the county of Essex and State of New Jersey, have invented certain new and useful Improvements in Cushions for Vehicles, of which the following is a specification.

This invention aims to provide a pneumatic cushion arranged to transmit the shocks arising in traveling over rough roads from the wheel to the vehicle body. For this purpose a cylinder and piston are provided connected preferably to the axle and to the wagon body respectively, together with means for providing and maintaining a determined pressure or pressures upon opposite sides of the piston. The stuffing box and the joints of the cylinder are made as tight as possible by ordinary means. For perfect retention of the cushion there is provided an elastic bag at each side of the piston in which the air is compressed or carried and from which it cannot possibly escape; the bags being arranged to substantially fill the spaces within the cylinder so that they are backed by the surrounding metallic walls and the material of the bag is not subjected to any substantial strain.

Other features of improvement are referred to in detail hereinafter.

The accompanying drawings illustrate an embodiment of the invention.

Figure 1 is a rear elevation of the apparatus with the adjacent parts of the vehicle to which it is applied. Fig. 2 is a vertical section through the cylinder. Fig. 3 is a plan of a ring used in connection with the piston packing.

Referring to the embodiment of the invention illustrated a cylinder A is fastened rigidly upon an axle B of the vehicle and a heavy piston rod C is fastened at its outer end to any suitable part D of the vehicle so that the piston rod (or rods where a plurality of such devices are used) carries the weight of the vehicle body and the cushion actually supports the load at all times such as the wagon body or any additional metallic spring. Preferably such a cylinder and piston would be applied one near each end of each axle of the vehicle; though any desired number and position of the cushions may be availed of. A broad connection is secured at the lower end by means of a strap E running around the axle B preferably fastened

thereto by stud bolts F and provided at its upper end with flanges G fastened to the bottom of the cylinder by similar bolts. A broad fastening is secured at the upper end of the piston rod by means of washers H and nuts J screwed on the piston rod.

The cylinder is formed of the tubular shell K open at both ends to permit accurate boring of the cylinder and easy assembling of the parts and is provided at its ends with outward flanges bolted to the bottom head L and the top head M. The upper cylinder head M is provided with a central stuffing box N through which the piston rod passes and each of the cylinder heads is provided also with smaller stuffing boxes O and P respectively through which pass the pipes for introducing the compressed air.

Within the cylinder, in the space above the piston is a bag Q of light rubber or similar air tight material and annular in shape and of such a height as to fill the space above the piston in the desired normal position of the latter. A similar bag R is provided substantially filling the space below the piston. Running through the stuffing box O is a pipe S which passes into the bag Q, the edge of the bag where the pipe passes through it being clamped between washers T and U by means of a nut V so as to make an air tight joint at this point. The bag R is entered by a similar pipe W. The pipes S and W after passing out of the heads of the cylinder are bent horizontally and are connected at opposite ends of a vertical pipe X which is connected by means of a pipe Y having a valve Z with an air pump. In the case of motor driven vehicles an air pump may be provided on the vehicle for inflating the cushion. Even where no such pump is provided, however, the cushion may be inflated from a separate pump and will not require reinflation for an indefinitely long time, barring accidents. Each of the branch pipes S and W is provided with a safety valve *a* adapted by the compression of its spring to be set for any desired pressure, and with a stop valve *b* whereby the connection of the cushion with the air compressor may be cut off. In addition preferably a pressure gage *c* is provided in the pipe X.

In order to inflate the apparatus it is set with the piston *d* at the desired height in the cylinder (say for example at the middle point, as shown) and a sufficient pressure of air is

pumped into the bag R to maintain the load upon the piston. This operation is effected by shutting off the stop valve of the pipe S and opening that of the pipe W. Thereafter the upper bag Q will be filled with air under such a pressure as will prevent the piston d and the wagon body connected therewith from being thrown too far upward. The pressures may be such for example that 10 the total pressures on opposite sides of the piston counterbalance each other, while each opposes a strong but elastic force to the movement of the piston.

To provide against the letting down of the piston in case air escapes from one or the other of the bags, it is provided on its opposite faces with cup leathers e held out against the cylinder wall by means of spiral springs f and having flanges g which are bent inward over said springs sufficiently to protect the bags from being cut thereby. Dished plates h are provided on the opposite faces of the piston in order also to make a smooth backing for the bags throughout the diameter of 25 the piston. The edges of these dished plates h extend out substantially to the springs f and tend to expand radially under the air pressure so as to hold the springs out.

It will be seen that the cushion described 30 provides a very efficient and comparatively cheap means of lessening the shock of traveling over rough roads and one which, by reason of the protection of the pneumatic bags, will be extremely durable and is in little or no danger of accidental injury or loss 35 of air; and even when the bags, by deterioration of age or otherwise cease to be perfectly air tight, the apparatus will still be effective for a considerable time by reason of the tightness of the various packings. The cushioning 40 effect is so great as to avoid the necessity for pneumatic tires on the wheels, at least in a great many types of vehicles. Very little rubber is necessary in the construction 45 of the apparatus and it is therefore substantially cheaper as well as more free from danger of injury than pneumatic tires.

Although the invention is designed especially for use in connection with vehicles and 50 is claimed broadly in this respect, yet the particular style of cushion illustrated is of especial value in various other situations. For example it may be used for the purpose of deadening noise on elevated railways and 55 similar structures by the introduction of a number of cushions at suitable points for transmitting the shock from the rails, ties, beams, girders, columns or the like; or at all points where the usual longitudinal girders 60 rest upon the cross girders. A gage of any sort may be provided for indicating when the

piston is in the intermediate or other desired position, for example lines j may be marked on the piston rod for the purpose. Where it is desired to allow a substantial amount of 65 play of the piston up and down and there is not space for a very long cylinder, the projecting parts of the pipes S and W may be countersunk in the heads of the cylinder.

What I claim is:—

1. An air cushion including in combination a cylinder A, a piston d therein, pipes S and W entering said cylinder at opposite sides of the piston for introducing a supply of compressed air therein, a safety valve and a 70 stop valve in each of said pipes S and W, a common pipe Y for supplying air to the opposite ends of said cylinder, and a stop valve Z in said pipe Y.

2. An air cushion including in combination 80 a cylinder, a piston d therein, air-tight flexible bags Q and R within the cylinder at opposite sides of the piston respectively, and pipes S and W passing through the cylinder and into said bags for introducing a supply 85 of compressed air therein, each of said pipes S and W being provided with a safety valve and a stop valve, and a common pipe Y for supplying air to said bags and provided with a stop valve Z.

3. An air cushion including in combination a cylinder and a piston d therein, bags of air-tight flexible material within the cylinder at opposite sides of the piston, cup leathers e for packing the piston and having inturned 95 edges g, and dished plates h protecting the bags from direct contact with the faces of the piston.

4. An air cushion including in combination a cylinder A, a piston d therein, air-tight flexible bags Q and R within the cylinder at opposite sides of the piston respectively, pipes S and W passing through said cylinder and into said bags for introducing a supply of compressed air therein, substantially 100 air-tight stuffing boxes through which the piston rod and said pipes S and W pass so as to prevent the escape of air from within the cylinder in case any air escapes from one of the bags, cup leathers e for packing the 110 piston and having inturned edges g, springs f for pressing the edges of the cup leathers against the cylinder wall, and dished plates h protecting the bags from direct contact with the faces of the piston.

In witness whereof, I have hereunto signed my name in the presence of two subscribing witnesses.

PATRICK F. GUTHRIE.
